H. L. C. WENK,
SEAL,
APPLICATION FILED DEC. 28, 1917.

1,267,725.

Patented May 28, 1918.

Henry L. C. Wenk
Inventor
By his Attorney
Fred Dasker.

UNITED STATES PATENT OFFICE.

HENRY L. C. WENK, OF BROOKLYN, NEW YORK.

SEAL.

1,267,725.

Specification of Letters Patent. Patented May 28, 1918.

Application filed December 28, 1917. Serial No. 209,245.

To all whom it may concern:

Be it known that I, HENRY L. C. WENK, a citizen of the United States, and resident of the borough of Brooklyn, in the county of 5 Kings, city and State of New York, have invented certain new and useful Improvements in Seals, of which the following is a specification, reference being had therein to the accompanying drawing.

10 My invention refers to box or package seals and the method of applying them for use. The object is to securely fasten a tin or metallic seal without nails or other securing means to the overlapping portions of a 15 metallic strap for boxes, packages or the like, so that they may be interlocked by the action of the punch in such a manner that the strap portions cannot be pulled apart, and hence will be held with great firmness upon 20 the box. The invention may be therefore said to consist essentially in the construction, arrangement and combination of the parts substantially as described and claimed.

In the accompanying drawing illustrating 25 my invention:—

Figure 1 is a plan view of the blank out of which the seal is formed.

Fig. 2 is a similar plan view with one section thereof struck up to form a passage.

30 Fig. 3 is a cross-section on the line 3, 3 of Fig. 2.

Fig. 4 is a plan view after the blank has been folded together.

Fig. 5 is a cross-section of the same on the 35 line 5, 5 of Fig. 4.

Fig. 6 is a plan view of the seal similar to Fig. 4, and shows the overlapping portions of a strap or cord passed through the seal.

40 Fig. 7 is a cross-section on the line 7, 7 of Fig. 6.

Fig. 8 is a cross-section of the same after the punch has acted thereon and punctured a hole through all of the parts for the purpose of combining and interlocking their sections together.

My improved seal which is made of tin or similar material, is formed from the blank shown in Fig. 1, which has a general rectangular form but shaped in two sections 1 and 2 between which are central indents 3, 3. The outer end of one of the sections 2 is provided with a recess 4, while the corresponding end of the other section 1 is provided with a lip 5 adapted to be bent to engage the recess 4, after the two sections 1

and 2 have been bent at the indents 3 so as to be superposed upon each other.

The blank thus shaped as shown in Fig. 1 is next acted upon in a suitable press or other machine, so that the section 2 may be formed with parallel slots 6, 6 between which is the struck up portion 7, which occupies the position shown in Fig. 3 when viewed endwise, the loop or socket being thus formed through which the sections *a* and *b* of the metallic strap or cord which is used to bind around the box or other package or article are passed, the portions overlapping each other in a manner shown in Fig. 6.

After this raised up loop or socket 7 has been formed, the blank will by suitable mechanical means be bent over on the indented points 3, 3 so that the section 1 may lie underneath the section 2; that is to say, on that side of section 2 opposite to the struck up loop 7 as clearly shown in Fig. 4, and when the parts are thus closed tightly together, the lip 5 will be bent over the edge of the section 2 in the recess 4 and bent down tightly upon the face of the seal closely adjacent to the loop 7, as clearly shown in Figs. 4, 5 and 6. The seal is now complete and ready for use. In cross-section the appearance of the seal at this time is shown in Fig. 5 where the struck up portion 7 is raised and the slots 6, 6 are open in readiness to receive the overlapping portions of the metallic strap of the box.

90 In the sectional view of Fig. 7 these overlapping portions *a* and *b* are shown in position as they are also indicated in Fig. 6, and it is clearly evident how the seal is related to the sections when they are all 95 tightly drawn together and the strap is located in proper position upon the package and they can be held so by proper puller devices and then by means of a suitable punch, as for example the punch shown in 100 my co-pending application for Letters Patent, filed October 12, 1917, Serial No. 196,110 or any other similar efficient instrument, a hole is punched as at *c* through all the overlying parts, that is to say the two 105 sections *a* and *b* and the top 2 and the bottom 1 of the seal interweaving and interlocking the fractured ends of all these parts, so that they will be intertwined and impossible to separate for they will occupy the position 110 shown in Fig. 8, and will be effectively related to each other, so that the seal will do

the work in a very satisfactory, strong, durable and firm manner. A seal of this kind will be found to be of great value because of its cheapness and simplicity.

5 In passing the ends *a* and *b* through the loop 7 and the slots 6, there might be danger of the ends of said sections striking against the edges of the slots, but I obviate any possibility of this by forming a couple of 10 raised lines, inclines or lifted ribs 8, 8 on the face of the section 7, which comes immediately adjacent to the loop 7 when the blank is folded into the form shown in Fig. 4; said ribs being close to the slots 6, 6. These 15 ribs may be formed in any desired manner. Simply running a small groove or two of them parallel to each other as shown in Fig. 2 on one side of the section 1 so as to produce slight raised lines on the other side 20 will be sufficient for the purpose, as ordinarily these raised ribs need not be any thicker or perhaps as thick as the material of the blank. All that I need is to provide slight raised ribs adjacent to the slots 6, 6

which will have the effect of lifting the 25 ends *a* and *b* of the strap in guiding them through the adjacent slots 6 and thus preventing said ends from striking against the edges of the slots.

Having thus described my invention, what 30 I claim as new and desire to secure by Letters Patent, is:

A seal consisting of two sections folded on a transverse middle line, one section having a lip engaging and folding into a recess 35 on the edge of the other section after the two parts are folded together, and one of the said parts having a struck up loop providing two parallel openings through which the strap to which the seal is to be attached 40 may be passed, and the other of said parts having one or more raised ribs to guide the strap into one or the other of said parallel openings, said ribs contiguous to and parallel with said openings. 45

In testimony whereof I hereunto affix my signature.

HENRY L. C. WENK.
